UNITED STATES PATENT OFFICE.

BRAMAH JOSEPH DIPLOCK, OF FULHAM, LONDON, ENGLAND.

VEHICLE.

1,202,814.

Specification of Letters Patent.

Patented Oct. 31, 1916.

Application filed August 24, 1915. Serial No. 47,190.

To all whom it may concern:

Be it known that I, BRAMAH JOSEPH DIPLOCK, a subject of the King of Great Britain, residing at 3 Wyfold road, Munster Road, 5 Fulham, London, England, have invented new and useful Improvements in Vehicles, of which the following is a specification.

I have before described a vehicle supported on feet carried by endless chains of 10 foot carriers running on rails fixed to the body of the vehicle, each foot being pivoted to the lower end of a rod which was suspended from the foot carrier and was surrounded by a compressed spring.

15 The object of the present invention is to provide improved means for connecting the feet of such vehicles to the foot carriers so that any sidewise, tilting or twisting displacement of a foot relatively to its carrier 20 may be resisted and that when a foot which has been so displaced is raised from the ground it will at once resume its proper position relative to its carrier. According to this invention each foot is suspended from 25 its foot carrier by two or more (preferably four) rods each surrounded by a compressed spring.

Figure 1 is a side elevation of the preferred arrangement and Fig. 2 is a section 30 on the line 2—2, Fig. 1. Figs. 3 and 4 are sections similar to Fig. 2 and showing the position of the parts when the foot is tilted and when the foot carrier is moved sidewise relatively to the foot. Fig. 5 is a plan 35 showing the foot carrier twisted about the foot. Figs. 6 and 7 show a rod with a modified head.

a is a slipper adapted to run on antifriction chains interposed between it and the 40 rail.

b is a foot carrier pivoted at c to the slipper a.

d is a foot suspended from the foot carrier by four rods e. The upper end of each rod 45 passes through a hole in the foot carrier and is provided with a nut f and washer g. The lower end of each rod passes through a hole in a plate h fixed to the foot and is provided with a head i which lies in a recess in the 50 foot and bears against the underside of the plate h.

k are compressed springs encircling the rods.

l is a central stem which is fixed to the un- 55 derside of the foot carrier and engages an

elongated recess m in a lug n on the plate h. This stem limits the relative movements of the foot and foot carrier.

o are rims formed on the upper side of the plate h to keep the lower ends of the springs 60 in position.

Fig. 3 shows the foot tilted relatively to the foot carrier, the left hand spring being accordingly further compressed.

Fig. 4 shows a sidewise displacement of 65 the foot relatively to the foot carrier. In this case the rods become inclined and the washers and heads are tilted so that they bear only on one edge, the foot carrier being brought nearer to the foot, the springs also 70 being further compressed.

Fig. 5 shows the foot carrier twisted about 75 the foot as a pivot. In this case also the rods are inclined and the springs are further compressed.

It will thus be seen that all displacements of the feet relatively to the foot carriers are resisted and when feet so displaced are lifted from the ground they at once resume their proper positions relatively to the foot carriers.

Figs. 6 and 7 show another device having the object of providing greater resistance to longitudinal relative movements than to transverse movements, the bearing faces of 80 the heads i being made elongated or elliptical so as to give a greater lift for the same tilt in the one direction than in the other. Similarly the washers g may be made elongated or elliptical or the bearing faces of 85 the heads or the washers or both may be irregularly beveled, or springs wound in an oval may be employed.

What I claim is:

1. The combination of a foot carrier having in it a plurality of holes, a foot also having in it a plurality of holes, a plurality of rods, the ends of each of which pass one through a hole in the foot carrier and the other through a hole in the foot means for preventing the ends of the rods from being withdrawn from such holes, and a spring surrounding each rod. 95

2. The combination of a foot carrier having in it a plurality of holes, a foot also having in it a plurality of holes, a plurality of rods, the ends of each of which pass one through a hole in the foot carrier and the other through a hole in the foot, means for preventing the ends of the rods from being 105 withdrawn from such holes, and a spring surrounding each rod. 110

withdrawn from such holes, and means for limiting the movement of a foot relative to its carrier.

3. The combination of a foot carrier having in it a plurality of holes, a foot also having in it a plurality of holes, a plurality of rods, the ends of each of which pass one

through a hole in the foot carrier and the other through a hole in the foot, means for preventing the ends of the rods from being withdrawn from such holes, a spring surrounding each rod, and means for limiting the movement of a foot relative to its carrier.

BRAMAH JOSEPH DIPLOCK.
